UNITED STATES PATENT OFFICE.

ART HADLEY, OF PROVIDENCE, RHODE ISLAND.

BRACELET-LINK.

1,292,763.

Specification of Letters Patent. Patented Jan. 28, 1919.

Application filed June 28, 1917. Serial No. 177,484.

To all whom it may concern:

Be it known that I, ART HADLEY, a subject of the King of Great Britain, residing at Providence, in the county of Providence and State of Rhode Island, have invented 5 a new and useful Improvement in Bracelet-Links, of which the following is a specification.

This invention relates to certain new and 10 useful improvements in a bracelet link and it has for a primary aim to provide a simply constructed link composed of two parts that may be formed very economically and assembled in a most facile and efficient manner.

The invention broadly consists of a pair 15 of connected side link parts and an interposed central link part having interlocking engagement with the inclosing side links 20 and constructed in the form of a hook or clasp for ready connection with an adjacent link.

In the drawings—

Figure 1 is a top plan view of the link 25 complete.

Fig. 2 is a side elevation thereof with one side link removed.

Fig. 3 discloses the link in bottom plan.

Figs. 4 and 5 are transverse sections on 30 lines 4—4 and 5—5, respectively of Fig. 2, and

Fig. 6 is a plan of the blank from which the central link is formed.

Referring more in detail to the drawings, 35 the side links 1 and 2 are preferably dished or hollowed in cross section and separably connected at their ends by studs 3 and sockets 4 that telescopically relate themselves in frictional engagement.

The central link 5 is formed from a single strip which is flattened at its opposite side edges and at spaced points to provide 40 oppositely extending ears or lugs 7 and 8. This strip is also formed with a U-shaped depression 9 transversely about which is bent and clenched a second strip 10, the latter extending from the opposite side edges of the link strip to serve in a like capacity with the ears 8 as will hereinafter 45 appear.

The link strip is bent in the form depicted to provide an upper length, which includes the transverse strip 10, and a lower length which constitutes a spring tongue 50 11. This tongue includes the ears 7 and the adjacent terminal 12 which is curved

to form a stop for defining the extent of inward movement of said tongue by abutting the upper length or base. From the depressed portion 9 the adjacent terminal 60 13 is curved and shaped to form a hook or keeper for the spring tongue, said hook bearing on the convex surface of terminal 12, the ears 7 affording additional bearing or riding surface therefor.

65 The central link is arranged between the side links with the ears 8 and the projecting portions of the strip or clip 10 engaging in the dished part of said side links to hold the central link from upward movement between the side members. The U-recess seats against the adjacent socket 4 to limit longitudinal movement. Thus the central member is securely and firmly held in position without interfering with the 70 75 free springing action of the tongue.

The central link part is economically stamped and formed from a single narrow strip of stock, and the several link parts may easily and securely be assembled in a 80 most efficient manner. Although the link is especially designed for bracelets, still it is obvious that it may readily be adopted for other constructions.

Having thus described my invention, 85 what I claim as new and desire to secure by Letters Patent is—

1. A bracelet link composed of spaced side link parts connected at their ends, each being dished in cross section, and a central 90 link part arranged between the side link parts and comprising a single strip bent upon itself to form a spring tongue and a coöperating hook, said central link part carrying oppositely projecting means extending into the dished portions of the side link parts at longitudinally spaced points, certain of said means being removable.

95 2. A bracelet link composed of spaced side parts, and an interposed central part formed of a strip of flexible material and comprising an upper length having means at longitudinally spaced points for interlocking with the side parts and a lower length connected to the upper length and 100 yieldable freely between said side parts.

105 3. A bracelet link composed of spaced side parts, and an interposed central part formed of a strip of flexible material and comprising an upper length having means 110 at longitudinally spaced points for interlocking with the side parts and a lower

- length connected to the upper length and yieldable freely between said side parts, the free end portion of the upper length terminating in a downwardly and backwardly directed hook, and the free end portion of the lower length being deflected from between the side parts into contacting relation with the hook end and flattened to provide a broad bearing for the latter.
- 10 4. A bracelet link composed of spaced link parts, each being dished in cross section and one having a laterally extending socket at each end and the other having a stud likewise disposed to enter the respective socket for uniting the parts, and a central link part arranged between the side link parts and comprising a single flexible strip having spaced pairs of ears formed by pressing the material from its opposite side edges, said strip being bent substantially on a line with one pair of ears to provide a spring tongue carrying the other pair of ears which afford a broad bearing surface for said hook and a return hook overlying

the latter pair of ears, said first pair of 25 ears interlocking with the side link parts.

5. In a bracelet link, a link part formed of a single strip having a pair of oppositely extending ears and a recess, said strip being formed into a clasp, a second strip bent 30 around the first strip and seated in the recess to provide oppositely extending portions, and a second link part with which the ears and second strip interlock.

6. A bracelet link comprising an open 35 link part, a central link part arranged within the first part and including upper and lower lengths, and longitudinally spaced means carried by the central link part and interlocking with the first part for holding 40 the central part in position.

In testimony whereof I have signed my name to this specification in the presence of two subscribing witnesses.

ART HADLEY.
